UNITED STATES PATENT OFFICE.

JOHN G. CALLAN, OF NAHANT, MASSACHUSETTS, ASSIGNOR TO GENERAL ELECTRIC COMPANY, A CORPORATION OF NEW YORK.

WIRE-COATING MACHINE.

1,031,620.

Specification of Letters Patent.

Patented July 2, 1912.

Application filed October 24, 1907. Serial No. 398,968.

To all whom it may concern:

Be it known that I, JOHN G. CALLAN, a citizen of the United States, residing at Nahant, county of Essex, State of Massachusetts, have invented certain new and useful Improvements in Wire-Coating Machines, of which the following is a specification.

This invention relates to machines for continuously applying a coating to a wire or 10 the like, and has for its object the provision of means whereby the various steps of the coating process may be accomplished in a reliable, simple and efficient manner.

My invention relates more specifically to 15 machines for applying a film insulation to electrical conductors. The film insulation is applied in liquid form and subsequently solidified. A single coating or a plurality of superposed coatings may be applied, as de- 20 sired, depending upon the specific nature of the material.

One of the objects of my invention therefore is to provide a machine of a compact, well organized construction, which will re- 25 duce the insulation of conductors to a successful operating basis, and produce an insulated wire of a satisfactory quality at commercial speeds.

Various other objects of my invention will 30 appear in the course of the following specification, in which my invention has been reduced to a concrete mechanism for purposes of illustration.

In the accompanying drawings which 35 illustrate one embodiment of my invention, Figure 1 is a sectional elevation of my complete coating machine; Fig. 2 is a front elevation of a part of the machine; Fig. 3 is a section taken on the line 3-3 of Fig. 1 looking 40 in the direction of the arrow; Fig. 4 is a plan view of the machine; Fig. 5 is a section of the coating and storage tank showing the position of the insulating fluid at the time the valve therein is first opened; Fig. 6 is a 45 plan view of the same; Fig. 7 shows the storage tank in tilted position; and Figs. 8, 9 and 10 show details of the coating mechanism.

Referring to the drawings, A is an oven 50 through which the conductor travels in the process of insulation; B is the stringing frame upon which the wire is strung; C is the spooling mechanism; and D is the fluid tank.

55 The oven A is the upper part of a vertical

rectangular box, the inside of which is made accessible by means of a door 10 pivoted at 11, raised by means of a weight 12 and normally held in closed position by means of a rope 13. Within this oven are the heating devices which are shown as heating coils 14. A driving shaft 15 is mounted in the lower part of the box and has secured thereto a wheel 16 which imparts a rotary movement to the wheel 17 and the wire carrying 60 sheaves 18. The upper sheaves 19 which carry the wire are mounted upon a shaft 20 supported by a member 21 which has a yoke at the top forming a bearing for the shaft and admitting the wire carrying sheaves between the bearings. This member 21 is supported by links 22 and 23 so that the latter have a parallel movement. The links are pivoted at their middle points to the arm 24 at 25 and 26 respectively and the outer ends 75 are pivoted at 27 and 28 to the rod 29. This rod is pivoted to a bracket secured to the frame at 30, and the arm 24 is similarly pivoted at 30'. Springs 31 are arranged as shown so as to normally draw the links 22 and 23 together and tend to have them assume a position parallel to rod 29. The springs lend flexibility to the shaft 20 and render the wire taut on stringing frame. When the door 10 is raised, the stringing 80 frame may be brought down to the position shown in dotted lines so as to permit of stringing wire over the sheaves. A sprocket wheel 32 is mounted upon the drive shaft 15 and communicates a rotary movement to a 85 sprocket wheel 33 on the shaft 34 by means of a sprocket chain 35. The sprocket wheel 33 is integral with a sprocket wheel 36 loosely mounted upon the shaft 34, the latter shaft being rigidly secured to the frame. 90

Pivoted to the shaft 34 is an upwardly extending arm 37, the upper end of which is formed into a yoke 38 to which the fluid tank D is pivoted at 39. Adjustably secured by means of the slot and bolt connections 40 are arms 41, the upward ends of which are pivoted at 42 to the outer end of the tank. By means of the bolt and slot, the tank can thus be moved on the pivot 39 so as to adjust the same as desired for the 105 purposes hereinafter set forth.

Mounted upon the tank D is a sprocket wheel 43 integral with a gear 44 meshing with a gear 45 driving the shaft 46 upon which the coating roller 47 is mounted. The 110

sprocket 43 is driven from the sprocket wheel 36 by means of a chain 48 so that motion is transmitted from the drive shaft 15 to the sprocket chain 35, shaft 34 and chain 5 48 to the coating roller 47.

Loosely mounted upon the shaft 34 is an arm 49 to which is secured a flexible bearing 50 for the intermediate driving wheel 17. A hub 52 on the arm 37 forms a bearing for 10 the screw 53 which bears against the arm 49. A spring 54 normally pulls the arm 49 outward so as to disengage the intermediate drive wheel and by turning the screw the intermediate wheel may be thrown in and 15 out of action. The arm 49 is also connected with the treadle 55 by link 56 so that the machine can be operated intermittently by the pressure of the treadle. When the arm 37 is moved so as to move the tank D away 20 from the machine, the spring 54, one end of which is connected with the arm 37, will move the arm 49 and hence the intermediate drive wheel 17 out of driving contact, and thus instantly stop the rotation of the wire 25 sheaves and the travel of the wire. An adjustable back stop 57 is rigidly secured to the frame so as to limit the backward movement of the arm 37. When the tank D is moved backward it will assume the position 30 shown in dotted lines in Fig. 1.

The tank D as shown is divided into three fluid supply compartments 59 and three coating compartments 60. The top 61 of the supply compartments is air tight and is 35 provided with tapering filling holes, one for each compartment, provided with plugs 62. The top of the tank 61 is angular as shown so that when the tank is tilted into the position shown in dotted lines there will be an 40 air-tight chamber 63 above the fluid when the tank is filled. When the tank is moved back to its operative position shown in full lines, the space 63 will be filled with fluid, and the air space will be changed in the position shown at 64. A tube 65 is threaded through the top of the tank as shown so that its upper end communicates with the atmosphere and the lower end opens into the tank near the bottom thereof. This tube may be 45 adjusted by screwing it up and down through the top by means of the slots in the top of the tube. The coating compartments of the tank connect with the filling compartment by a passage-way 66, and the holes 67 located at the undersides of the tank connect with this passage so as to drain both 50 compartments through the said passageway when desired, the holes being provided with plugs 68, that have slots or valves 69 which 55 permit the liquid to flow from one compartment to the other. By turning the plug 68 communication between the two compartments is cut off. Adjacent to the partition 60 70 between the two compartments are plates 65 71 rigidly held against the partition by

means of a bolt 72 and nut 73. The upper portions of the plates are formed into U-shaped arms 74 to support the transfer wheels 75. These transfer wheels are located so as to run in the slots of the coating roller 47 through which the wire 58 runs to be coated. Fluid is kept at a definite level within the coating compartment so that the transfer wheel dips into it and the plugs 76 may be removed to drain off this compartment. A cover 77 is provided for the coating compartment having a window 78 to enable the operator to note the height and condition of the coating fluid. A scraping device 79 having projections which fit into the grooves of the coating wheels is located in the tank so as to prevent lumps of the coating material being carried on to the wire. This scraper is held in the grooves by means of the spring 80 and a screw 81 is provided 80 which prevents the scraper from dropping back into the compartment. The scraper is forced against the plate 82 by the rotation of the coating wheels. A plate 83 is provided to protect the roll. If for any reason 85 the coating feeds unevenly to one or two of the wires, and the operator considers it necessary to cut out any of the transfer wheels, it can easily be done by turning the nut 73 which will draw the transfer wheel away 90 from the coating roller. 95

The spooling mechanism is operated from the drive shaft 15 by means of a sprocket chain 84 which drives a stub shaft mounted in bearings on the main frame, which shaft drives a vertical shaft 85 through bevel gears 86. At the upper end of the shaft 85 is a bevel gear 87 driving a shaft 88 to which is secured a friction wheel 89 co-operating with a bevel friction gear 90 mounted on shaft 91. 100 This shaft 91 has a bearing in the bracket 92 pivoted to the main frame, and at its outer end is secured the spool 93 upon which the wire is wound after it is insulated. The bracket 92 is pivoted on a shaft 94, and the friction gears 89 and 90 are held in contact by means of the adjustable weight 95. The wire is led across the spool by means of a cam 103 which is caused to rotate by means of threads on the shaft 85 and the worm gear 96. This cam 103 causes the rock shaft 97 to be moved back and forth by means of the arm 98 having a roller at its outer end co-operating with the face of the cam. A rod 99 is adjustably secured to the shaft 97 and has at its outer end a roller 100 which, as the shaft 97 rocks, leads the wire across the spool while the tension of the wire brings it back. The wire is fed from a similarly operated spool 101 which, however, requires no feeding mechanism so that the wire passes off the spool 101 thence down to the lower sheaves 18 up through the oven and back and forth from the lower to the upper sheaves until it is wound on the spool 93. 115 120 125 130

The shaft 88 may have a number of friction gears 89 and 90 attached thereto to operate all of the spooling devices simultaneously, and the rock shaft 97 may similarly operate a number of the guiding rollers.

5 The operation of my machine will be clearly understood from the foregoing description. The pulley 102 transmits power to the spooling mechanism through the shaft 85 and likewise to the coating rollers through the sprocket 33 and chain 48. To fill the coating tank, the latter is moved out from the coating rollers so that it will be in a tilted position shown in dotted lines in Fig. 10 15. The tank is then filled with the passage 66 to the coating compartment closed. An air space is thus left in the chamber 63. The tank is then moved back to its operative position and the air space will be transferred to the position shown at 64. Communication is now opened between the coating and storage compartments by means of 20 the valves or slots 69 in the ends of the plugs 68. The fluid will then rise in the coating compartment above the level of the lower extremity of the tube 65. After the machine has run a short time, however, the fluid is consumed until it reaches the level 25 of the lower end of the tube which is the permanent working level of the fluid. The tube 65 communicating with the atmosphere and the coating compartment being under atmospheric pressure keeps the level constant. When the fluid flows from the storage compartment into the coating tank, the 30 space 64 above the fluid is considerably increased causing the air to expand so that a slight vacuum will be maintained therein. This vacuum is sufficient to support the amount of fluid within the tank. In the 35 feeding operation as the fluid in the feeding compartment is reduced, the level in the coating compartment will fall below the bottom of the tube 65. This unbalancing allows air to enter the liquid through the tube in sufficient quantity to compensate for the increased space caused by the new supply fed into the coating compartment. In 40 this way the fluid in the coating compartment of the tank is maintained at a constant level. When it is desired to clean out the coating compartment, the tank may be tilted back and the plug 68 closed so as to keep the fluid in the supply compartment. 45 The tank may then be washed out and the washing fluid allowed to run out by removing the plugs 76.

50 The arrangement of the coating tank above described has many advantages in that the level of the fluid is always constant, and the fluid, which is oftentimes of a volatile nature, is kept entirely inclosed.

55 Various modifications of my invention will, of course, suggest themselves to those skilled in the art without departing from

the spirit of my invention, the scope of which is set forth in the annexed claims.

What I claim as new and desire to secure by Letters Patent of the United States, is,—

1. A wire coating machine comprising a 70 movable tank, means for bringing a wire to be insulated into engagement with an insulating medium, and means for automatically stopping the movement of the wire when the latter is moved.

75 2. A wire coating machine comprising a movable tank having a coating and a storage compartment communicating with each other, a coating wheel located in said coating compartment, means for passing the wire adjacent to said coating wheel, and means for automatically stopping the movement of the wire when the tank is moved.

80 3. A wire coating machine comprising a fluid tank having a coating compartment 85 and an air-tight storage compartment communicating with each other, a coating wheel located in one of said compartments, means for causing the wire to travel adjacent said wheel, and a tube leading from the atmosphere to a point within said latter compartment below the fluid level.

85 4. A wire coating machine comprising a pivoted tank having a coating compartment and an air-tight filling compartment 95 communicating with each other, means for carrying the wire into engagement with the insulation carrying means, and means for automatically stopping the movement of the wire when the tank containing the insulating medium is moved on its pivot.

90 5. A wire coating machine comprising a pivoted tank provided with a coating compartment and an air-tight filling compartment 105 communicating with each other having different positions for operating and filling, a coating wheel located in one of said compartments, means for causing the wire to travel adjacent said wheel, means for forming an air pocket above the fluid 110 level, and a tube leading from the atmosphere to a point below the fluid level in the storage compartment.

105 6. A wire coating machine comprising a movable fluid tank having a coating compartment and an air-tight storage compartment 115 communicating with each other, means for maintaining a constant level in the coating compartment irrespective of the level in the storage compartment, means for carrying the wire into engagement with an insulation conveying wheel in the coating compartment, and means for automatically stopping the movement of the wire when the tank is moved.

120 115 7. A wire coating machine comprising a pivoted fluid tank having a coating compartment and air-tight storage compartment communicating with each other, means 125 for forming an air chamber above the fluid 13

in said latter compartment, and a tube leading from the atmosphere to a point within the air-tight compartment below the fluid level, a coating wheel located in one of 5 said compartments, and means for causing the wire to travel adjacent said wheel.

8. A wire coating machine comprising a pivoted fluid tank having a coating compartment and an air-tight storage compartment, said latter compartment being supplied with a chamber for trapping air when the tank is filled, means whereby the tank may be moved to cause fluid to flow into the coating compartment and fill said chamber, and a tube leading from the atmosphere to a point below the level of the fluid 15 in the storage compartment.

9. A wire coating machine comprising a pivoted fluid tank having a coating compartment and an air-tight storage compartment, said latter compartment being supplied with a chamber for trapping air when the tank is full, means for carrying the wire into engagement with an insulation 20 distributing wheel in the coating compartment, and means for automatically stopping 25

the travel of the wire when the tank is tilted.

10. A wire coating machine comprising a pivoted fluid tank having a coating compartment and an air-tight storage compartment, said latter compartment being supplied with a chamber for trapping air when the tank is filled, means whereby the tank may be moved to cause fluid to flow into the 30 coating compartment and fill said chamber, a tube leading from the atmosphere to a point below the level of the fluid in the storage compartment, means for carrying a wire into engagement with an insulation 35 distributing means in working relation with the coating compartment, means for automatically stopping the travel of the wire when the tank is moved, and means for moving the tank on its pivot. 40

In witness whereof, I have hereunto set my hand this twenty first day of October, 1907.

JOHN G. CALLAN.

Witnesses:

JOHN A. McMANUS, Jr.,
HENRY O. WESTENDARP.
